UNITED STATES PATENT OFFICE.

CHARLES C. ALLEN, OF KANSAS CITY, MISSOURI.

LIQUID-MEASURER.

No. 921,336.

Specification of Letters Patent.

Patented May 11, 1909.

Application filed March 27, 1908. Serial No. 423,579.

Be it known that I, CHARLES C. ALLEN, a citizen of the United States of America, residing at Kansas City, in the county of Jackson and State of Missouri, have invented certain new and useful Improvements in Liquid-Measurers; and I do hereby declare that the following is a full, clear, and exact description of the invention, such as will enable others to make and use the same, reference being had to the accompanying drawing, forming a part of this invention.

In the minute division of liquids for various purposes, it becomes difficult and laborious to obtain at different times the same specific amount, as is well-known, in compounding pharmaceutical and other preparations.

The principal object, therefore, of the invention is to obtain repeated discharges from a body of liquid of equal minute quantities, and whereby the discharges may be confined to a specific quantity of the liquid.

The invention consists in the novel construction and combination of parts, such as will be first fully described and then specifically pointed out in the claims.

In the drawings,—Figure 1, is a side view in elevation of the liquid measuring instrument. Fig. 2, is a vertical sectional view of the same showing one of the planchets broken away. Fig. 3, is a detail view of the upper portion of the liquid holding tube partially in section. Fig. 4, is a horizontal sectional view taken upon the line x, x , on Fig. 1. Fig. 5, is an enlarged view in perspective of the strip from which the liquid measuring planchets are separated or punched.

Similar numerals of reference indicate corresponding parts in all the figures of the drawing.

Referring to the drawings, 10, indicates a receptacle for holding a quantity of liquid and for many purposes, such as for acids or liquids of a poisonous nature, which is as shown, in the form of a tube, quite small in circumference, and made preferably from glass. Upon the outer surface of the tube 10, at a point a short distance downwardly from its upper end, is a flange 12, extending around the tube and formed integral therewith. A flat inwardly turned portion 14, of the sides of the tube 10, closes the lower end of the tube and from the outer surface of said portion 14, extends a short projection or nozzle 15, terminating at a point, through which nozzle extends a small capillary dis-

charge opening 16, which also extends through the end 14, of the tube and communicates with the interior of the tube. In the upper end of the tube 10, which forms the receptacle for the liquid is fitted quite snugly a movable diaphragm or stopper 17, composed of wood, cork or other material.

18, indicates a sleeve which extends around and fits closely the upper portion of the tube 10, the lower end of the sleeve bearing upon the upper surface of the flange 12. Upon the upper end of the sleeve 18, which is in line horizontally with the upper end of the tube 10, is a circular base plate 19, which extends outwardly a short distance from the line of the outer surfaces of the sleeve, and is formed integral therewith, this plate forming the base plate of a case or chambered member hereinafter described. In the central portion of the plate 19, is a feed opening 20, of the exact circumference, of the inner circumference of the tube 10, the sides of which opening 20, extend over the upper end of the tube 10, and are in a vertical line with the inner vertical surface of said tube. Upon the outer surface of the sleeve 18, is a screw thread 21, extending the length of the sleeve and projecting outwardly beyond the line of the flange 12, on tube 10.

22, indicates a collar, upon the inner surface of which are screw threads 23, which collar is turned upon the sleeve 18, the upper portion of the collar extending upwardly to and fitting closely the lower surface of the plate 19. The inner portion 24, of the lower end of the collar below the screw threaded portion 23, extends to the flange 12, and a short distance below the said flange and thence is bent at right angles and extending inwardly to the tube 10, forming a flange 25, between which flange and the lower surface of the flange 12, on the tube 10, is a circular recess 26, in which recess is a rubber gasket 27. Upon the outer surface and lower end of collar 22, is an extended milled portion 22^x. Upon the upper surface of the base plate 19, is a cylindrical casing 28, of the same circumference as said plate, and which extends upwardly a suitable distance to afford the requisite space for a measured downward movement of the planchet cutter hereinafter described. Within the casing 28, which is of the proper thickness, is the chamber 28^x, in which the planchets are formed. The casing 28, is secured to the

base plate 19, by the screws 29, passing through said latter plate into the casing. Upon the upper end of the casing 28, is an inwardly extended plate 30, forming the top 5 to the chamber 28^x, within which plate is a circular opening 31, the circumference of which is approximately the same as that of the tube 10. Rigidly connected with the upper surface of the flange 30, and extending 10 around the opening 31, is a collar 32. Within the collar 32, and the opening 31, in the top plate 30, is the planchet cutting tube or die 33, the outer surface and lower end of which tube or die is inclined downwardly and in- 15 wardly at 34, terminating in a sharp edge. Connected rigidly with and extending around the outer surface of the tube 33, at a point immediately above the inclined surface 34, is a flange 35, which flange limits the up- 20 ward movement of the tube 33. The upper end of the cutting tube 33, extends a short distance upwardly above the line of the collar 32, and is externally screw threaded at 36, at said end. Upon said screw threaded 25 end of the tube 33, is an internally screw-threaded collar 37, upon the upper portion of which collar is an inwardly extended plate 38, in which plate is an opening 39, smaller in circumference than the inner circumfer- 30 ence of the planchet cutting tube 33. Extending around the tube 33, between the collars 32 and 37, and bearing upon each, is a spiral spring 40, which yields easily to compression, the tendency of which spring 35 is to maintain the cutting end of tube 33, normally in an upward or retracted position.

Within the tube 33, is a plunger 41, the upper portion of which plunger is reduced in circumference, to form a shoulder 41^x, which 40 comes into contact in its normal position with the inner surface of the plate 38, on the collar 37, the lower end of the plunger in said position being upon a line transversely with the flange 35, on the planchet cutting tube 45 or die 33. The reduced upper end portion 42, of the plunger 41, extends upwardly a suitable distance from the portion within tube 33, and its extreme upper end is screw threaded at 43. Upon said upper end 42, of 50 the plunger is a cap 44, upon which is a downwardly extended, internally screw threaded portion 45, engaging the plunger. Upon the reduced upper end portion 42, of the plunger, beneath the nipple 45, is a sleeve 55 46, upon the upper end of which sleeve is an outwardly extended flange 47, which flange fits against the lower end of the nipple 45. The lower end of the sleeve 46, extends downwardly the same distance as that be- 60 tween the cutting edge of the inclined lower end of the planchet cutting tube or die, 33, and the entrance to the opening 20, in the base plate 19, of the chamber 28^x. Extending around the sleeve 46, is a spiral 65 spring 48, the thickness of the wire and the

resistance to compression being greater than that of the spring 40, the upper end of which spring 48, bears upon the flange 47, on sleeve 46, and the other end upon the plate 38, on the collar 37, on the planchet cutting tube 33. 70

In the sides of the casing 28, directly opposite in position are the feed openings 49. These openings extend a short distance upwardly from the base plate 19, and approximately to the distance from the cutting edge 75 of the tube in its normal position and the entrance to the opening 20, in the base plate 19, these openings being in line transversely to the opening 20, and in width corresponding to that of the liquid holding tube 10. 80

50 indicates a strip of material which in width nearly corresponds to the width of the opening 49, in the casing 28, and in thickness is made specifically to afford a thin stopper for a proportionate displacement of liquid 85 in the tube 10, as further described. This strip as seen in Fig. 5, enlarged, may be made from paraffin wax, soap, vegetable fiber or analogous substances. In the employment and operation of the instrument, the collar 90 22, on the sleeve 18, is first removed and the tube 10, readily drawn from the sleeve. The tube 10, is then supplied with the proper liquid until the tube is filled, and the principal stopper 17, is then inserted within the 95 upper open end of the tube 10, as seen in Fig. 3, the stopper completely filling the space above the liquid, and also with its outer surface upon a line or even with the upper end of the tube. 100

The liquid within the tube without further pressure will remain in a compact body, the atmospheric pressure preventing the liquid from escaping through the capillary orifice 16, in the nozzle 15. The upper end of the 105 tube is then replaced within the sleeve 18, and the collar turned upon the sleeve, the gasket 26, preventing undue pressure upon the flange 12. One end of the strip 50, is inserted within one of the feed openings 49, in the chambered member 28, and placed over the upper end of the opening 20. Downward pressure is then applied to the cap 44, on the plunger 41, and under this pressure the weaker spring 40, upon the plunger 110 yields to the pressure, and the plunger moves downwardly and the planchet cutting die or tube 33, is also forced downwardly, the cutting edge upon the tube moving downwardly to the upper portion of the sides of the opening 20, in the base plate 19, separating from the strip 50, circular piece or planchet 50^x, of same circumference as the opening 20. Increased pressure is then applied to the cap 44, and the plunger within the tube 33, 115 moves downwardly with its lower end upon the planchet and forces the planchet within the feed opening 20, the said lower end of the plunger being then upon a line horizontally with the cutting edge of tube 33, and its 120 125 130

further measured movement checked by the contact of the lower end of sleeve 46, with the upper surface of plate 38. In the initial operation, the planchet first separated from 5 strip 50, remains within the opening 20, in the base plate 19, and pressure removed from the plunger, which, under expansion of the springs 40 and 48, resumes its normal position. The strip 50, is again moved in the 10 opening 49, of chamber 28^x, and pressure again applied to the plunger and another planchet separated from strip 50. In the completion of this latter movement, the lower end of the plunger forces the stopper 15 17, downwardly within the tube 10, the same distance as that of the thickness of the first planchet, the said planchet being within the upper end of the tube 10, and the second planchet being in a position with its upper 20 surface in line horizontally with the upper surface of the base plate 19, and the lower end of the plunger 41, in contact with the upper surface of the said planchet. Under the pressure applied to move the stopper 25 within the tube, and which now displaces an amount equal to the cubical contents of the planchet, an amount of the liquid equivalent to the amount displaced by the planchet, is discharged through the passage 16, in the 30 capillary tube or nozzle 15. These discharges may be slowly made in drops, according to the pressure applied to the plunger. Upon releasing the pressure upon cap 44, under the expansion of the springs 40 and 35 48, the plunger and the cutting tube 33, move upwardly into their normal positions. Upon a requirement for further discharge of the liquid from the tube 10, the strip 50, is moved within the chamber 28^x, in the direction of the other opening 49, and another portion of the strip is in position to receive 40 the cutting edge of the tube 33, and the operation repeated. The repeated operation described will advance the stopper 17, toward the end of tube 10, until the said tube 45 is completely filled with the stopper and the planchets, cut from the strip 50, and fed to the tube and the liquid is fully expelled, a new tube being inserted in the sleeve 18, supplied with the liquid and stopper as before.

It is observable that for the purposes of general use, a large number of tubes 10, may be filled with the liquid and used when required, and after use thrown away, the liquid 55 in the meantime being unaffected by exposure to the atmosphere. The precise number of drops required in certain preparations in order to obtain successful results, may be instanced in the use of glacial phosphoric acid in the making of cement for dental uses, and for the administration of powerful medicinal preparations in which the precise quantity discharged is of great 60 importance, the advantage being that the number of planchets used will indicate the

measured amount of the liquid discharged. It is obvious that the strips from which the planchets are made may be of different thickness, it being the purpose of the invention to so prepare the strip 50, that the planchets 70 separated therefrom will displace a given amount of liquid from the tube.

The invention is applicable to various uses and receptacles of various sizes from which the discharge of a specific amount of liquid 75 is necessary and the invention affords a means for accurately apportioning liquids.

Having fully described my invention, what I now claim as new and desire to secure by Letters Patent is:

1. A liquid measurer consisting of a receptacle or container for liquids having a capillary discharge opening, a stopper movable within the receptacle, and adapted to displace said liquid in small quantities suitable 85 pressure imparting means and superposed planchets co-acting therewith for advancing the stopper a distance determined by the thickness of the respective planchets.

2. A liquid measurer consisting of a receptacle or container for liquids having a restricted discharge opening and a stopper movable within the receptacle adapted to displace said liquid in small quantities and superposed planchets for advancing the 95 stopper within the tube with means for imparting pressure co-acting with the planchets for advancing the planchets a distance determined by the thickness of the respective planchets.

3. A liquid measurer comprising a receptacle or container for the liquid having a restricted discharge opening for discharging a minute quantity of the liquid, suitable liquid displacing devices and a feeder for feeding 105 said devices to the receptacle.

4. In liquid measurers the combination with a receptacle for the liquid having a small or restricted discharge opening, a movable diaphragm adapted to displace said liquid in 110 small quantities, a chambered member and connecting means connecting said member with said receptacle and self retracting pressure imparting devices movable within said chambered member planchets co-acting with 115 said devices adapted to move said diaphragm a determinate distance and means for actuating said devices.

5. In liquid measurers, the combination with a tube for holding the liquid having a 120 capillary discharge opening, a chambered member connecting means connecting the chambered member with said tube, a stopper movable within said tube, planchets within said tube imposed upon the stopper and 125 means adapted to be extended within the chambered member for feeding the planchets to the said tube.

6. In liquid measurers the combination with a tube for holding the liquid having an 130

opening at its upper end, and a capillary discharge opening at the lower end,—a chambered member having an opening registering with the opening in the upper end of said tube, connecting means connecting said chambered member with said tube, a strip of suitable material extending within said chambered member separating devices for separating a measured portion of the said strip, and pressure imparting means co-acting with the separated portion and separating devices forcing said portion of the strip within the said tube.

7. In liquid measurers the combination with a tube for holding the liquid having an opening at its upper end, and a capillary discharge opening, a chambered member having an opening at the lower end registering with the opening in the upper end of said tube, connecting means connecting said chambered member with said tube, a strip of suitable material and separating devices for separating measured portions thereof extending within the chambered member, and pressure imparting devices co-acting with the separating devices to force the separated portions of the said strip within said tube.

8. In liquid measurers the combination with a tube for holding the liquid having an opening at its upper end, and a capillary discharge opening at the lower end, a chambered member having an opening registering with the opening in the upper end of said tube, connecting means connecting said chambered member with said tube, said chambered member also having feed openings, a movable die within said chambered member, and a strip of suitable material extending within the chambered member and pressure imparting devices actuating said die, and forcing the portions of said strip separated by the die within said tube.

9. In liquid measurers the combination with a tube having an opening at its upper end, and a capillary discharge opening at the lower end a chambered member, having an opening registering with the opening in the upper end of said tube, connecting means connecting said chambered member with said tube, said chambered member having feed openings, a strip of suitable material extending within said chambered member planchet cutting devices adapted to separate the planchets from said strip and pressure imparting devices, co-acting therewith to force the planchets within said tube, and means for retarding the movement of the pressure imparting devices.

10. In liquid measures the combination with a tube for holding the liquid having an opening at its upper end, and a capillary discharge opening, a chambered member having feed openings and an opening at the lower end registering with the opening in the upper end of said tube, means connecting

said chambered member with said tube, a strip of suitable material extending within said chambered member through said feed openings, a planchet cutting tube adapted to separate the planchets from said strip within said chambered member, a collar on said tube, and a plunger having a cap co-acting therewith and movable within said cutting tube and acting to force the planchets within the tube, for holding the liquid and variable pressure controlling springs upon said plunger and between the cap thereon and the collar on said cutting tube and between said collar and the chambered member adapted to permit the prior action of the cutting tube.

11. In liquid measurers the combination with a tube for holding the liquid having an opening at its upper end, and a flange upon its outer surface and a capillary discharge opening, of a sleeve having an outer screw threaded portion, a base plate connected with said sleeve having an opening corresponding in size to and registering with the opening in the upper end of said tube, a casing connected with the base plate, a stopper movable within said tube alternate pressure imparting and recoiling planchet cutting devices connected with said casing, and an internally screw threaded collar upon said sleeve and a flange in said collar supporting the flange on said tube.

12. In liquid measurers, the combination with a tube having an opening in its upper end and an external flange, and a capillary discharge opening at its lower end, of an externally threaded sleeve upon said tube, an internally screw threaded collar upon said sleeve, having an inwardly extended flange and a recess and a gasket in said recess beneath the flange on said tube, a base plate connected with said sleeve having a feed opening corresponding in size to and registering with the opening in upper portion of said tube, and a casing connected with the base plate having an opening in the top thereof, a tube within said opening having a cutting edge, a plunger within said tube, having a reduced upper portion and a shoulder, a collar upon said tube having a flange extending over said shoulder, a cap on said plunger, a sleeve upon said plunger beneath said cap, and extending downwardly a predetermined distance, a spiral spring upon the sleeve upon said plunger bearing upon said cap and the said flanged collar on said cutting tube, and a separate spiral spring bearing upon said flanged collar and the casing.

13. In liquid measurers, the combination with a tube having an opening in its upper end and an external flange and a capillary discharge opening at its lower end, of an externally screw threaded sleeve upon said tube, an internally screw threaded collar upon said sleeve, having a flange and a re-

- cess, a gasket within said recess, a base plate connected with the said sleeve, having an opening of the approximate size to that of said tube and registering with the opening in 5 said tube in the upper portion thereof, a casing connected with the said base plate having an opening in the top and feed openings in the side thereof, a tube within said opening in the top of said casing having a 10 cutting edge upon its lower portion, a plunger within said tube having a portion reduced in circumference and a shoulder, a collar upon said cutting tube having a flange bearing on the shoulder on said plunger and a spiral spring upon said plunger between said collar 15 on said cutting tube and the top of said casing, a cap upon said plunger, a sleeve upon the reduced portion of said plunger extending downwardly a predetermined distance and a spiral spring bearing upon said cap 20 and the flange in the collar on said cutting tube.
